UNITED STATES PATENT OFFICE.

GEORGE H. BABCOCK, OF PLAINFIELD, NEW JERSEY.

ROOFING AND SHEATHING TILE.

SPECIFICATION forming part of Letters Patent No. 430,363, dated June 17, 1890.

Application filed November 8, 1889. Serial No. 329,678. (No model.)

To all whom it may concern:

Be it known that I, GEORGE H. BABCOCK, a citizen of the United States, residing at Plainfield, in the county of Union and State of New Jersey, have invented certain new and useful Improvements in Roofing and Sheathing Tiles, of which the following is a specification, reference being had to the accompanying drawings, in which—

10 Figure 1 is a plan view of several tiles embodying my invention arranged as they would lie upon a roof; Fig. 2, a vertical section taken on the line $x-x$, Fig. 3, showing the tiles combined as in Fig. 1; and Fig. 3, a face view of a 15 single tile, represented on an enlarged scale.

My improvement relates to clay or other tiles which are rectangular, or nearly so, in form and abut at the sides in continuous rows lengthwise of the roof, being laid so as to 20 "break" joints (shingle fashion) between consecutive rows.

The novelty consists in applying to this character of tile a downturned flange at its lower edge, or "reveal," giving a high relief 25 to the same, and conforming the adjacent portion of the underlying tile with an upward bend or wave near its middle, which fits the downturned flange of the overlying tile so as to bring every part of the adjacent lapping- 30 surfaces closely together and effect the sealing of the abutting joints. An upturned flange is also provided to the uppermost edge of the tile, which flange interlocks with and beneath the adjacent upward bend or wave 35 of the overlying tiles to prevent penetration of wind, rain, or dust between the part of the abutting joints that intersect said upward bend or wave of the overlying tiles.

The upper and lower portions A and B of 40 the tile lie in distinct planes joined by the offset or wave portion α . When the tiles are

combined, a double thickness of the material is formed throughout the roof, thereby closing the space beneath the abutting joints between the plain edges b at every part. 45

c represent the downward flanges, terminating the exposed surfaces of the tiles, and d the upward flanges, terminating the underlying ends thereof.

The tiles may be lightened by cutting off 50 portions of the upper half, as shown in dotted lines in Fig. 3, without interfering with their tightness.

The tiles may be secured to the substructure by any suitable mode or device. I have 55 illustrated that of providing ears e , having perforations for the reception of nails.

By the interlocking of the flanges at the ends with the wave in the center the tiles are rendered mutually supporting, so that should 60 the fastening of any one become loosened it cannot fall and endanger persons below, as is the case with common shingle-tile and slate.

What I claim as my invention, and desire to secure by Letters Patent, is— 65

1. In a tile, the combination of a downward flange across its lower end and an upward bend or wave extending across the tile near its middle.

2. In a tile, the combination of a downward flange across its lower end, an upward bend or wave extending across the tile near its middle, and an upward flange at its upper end.

3. In a tile, the combination of an upward wave across the middle and an upward flange 75 or bend across its upper end, substantially as described.

GEO. H. BABCOCK.
